UNITED STATES PATENT OFFICE.

WILLIAM HOCHHAUSEN, OF NEW YORK, N. Y.

SWITCH AND HOLDER FOR INCANDESCENT ELECTRIC LAMPS.

SPECIFICATION forming part of Letters Patent No. 357,385, dated February 8, 1887.

Application filed March 13, 1884. Serial No. 124,026. (No model.)

To all whom it may concern:

Be it known that I, WILLIAM HOCHHAUSEN, a citizen of the United States, and a resident of New York, in the county of New York and State of New York, have invented certain new and useful Improvements in Switches and Holders for Incandescent Electric Lamps, of which the following is a specification.

My invention relates to the construction of switches and holders for incandescent electric lamps; and its object is to simplify and improve the construction, to prevent burning of the switch-contacts, and to provide for the ready and convenient renewal of the parts, more especially of the fusible safety-wire in the lamp-circuit, which is arranged to fuse and break the circuit of the lamp upon a dangerous increase in the electric current.

My invention consists in certain details of construction and combinations of parts that will be hereinafter described, in connection with the accompanying drawings, and will be stated specifically in the claims.

In the drawings, Figure 1 is an elevation of a lamp containing a switch and holder constructed according to my invention. Fig. 2 is a vertical central section of the same on the line 2 2 of Fig. 3. Fig. 3 is an elevation of the switch and holder with the outer casing removed, in order to permit the details of construction to be seen, but with the removable base or block, to which the lamp is secured, reversed in position from the position shown in Fig. 2. Fig. 4 is a horizontal section on the line 4 4 of Fig. 2. Fig. 5 is a plan of a removable lamp base or block to which the lamp is secured. Fig. 6 is a horizontal section on the line 6 6 of Fig. 3. Fig. 7 is a vertical section of the cylinder or casing containing the switch mechanism, and illustrates the fastening or holding device by which the lamp provided with its attached base is connected to the upper end of said casing, as to a switch or holder. Fig. 8 is a vertical central section of a modification and illustrates the construction adopted when no switch is employed. Fig. 9 illustrates in elevation the detachable lamp base or block, and in plan the socket or holder to which it may be secured.

A indicates a base-plate, of metal or other suitable material, provided with a thimble, b, having a screw-thread by which it may be se-

cured to a bracket or other suitable support and made to form a passage for the insulated conductors a a², carried through the bracket or support and connected to the lamp-switch, as will be presently described. The plate A carries a block, B, preferably of insulating material, that forms a support for the switch mechanism and the contact springs or surfaces by which the lamp-terminals may be placed in electrical connection with the switch and conductors a a², and also carries the cylinder C, of brass or other suitable material, that serves to protect the switch mechanism, and is fastened in place by a screw, d, passing into the block B, or by other suitable means. The block B is fastened to the plate A by screws e or other device, and is cut away at its bottom portion over the opening in plate A, so as to form a space for the entrance of the insulated conductors a a². It also has a vertical slot or opening, as shown, to form a space for the play of two contact-springs, E E², secured to the block, and of a cam, D, of insulating material, secured to the horizontal spindle of thumb-piece F, lying outside of casing C. The block D is made in the form of a rectangle, in order to furnish sharp angles at the portion bearing against the springs, so as to give a snapping action in opening and closing the switch.

The springs E E² by their resiliency tend to spring inward toward one another when the cam D is given a quarter-turn in either direction from the position shown in Fig. 1, but are held by said cam in connection with two contact plates or surfaces, G G², of any suitable kind, when the cam is in position shown. The plates G G² are fastened to opposite sides of the block B, and their ends project over the vertical slot on the block and into the path of the springs E E². The plates G G² are electrically connected by means of the fastening bolt or screw g, or by other suitable device, and serve to complete the electrical connection between the springs E E², when the latter are forced into contact with them by the cam D.

H H² indicate two contact-springs mounted at the top of block B and lying in a horizontal plane. One of them, H², is directly connected with, or forms an extension of, the spring E², but the other is insulated from E. These springs H H² are insulated from one an-

other and form the means whereby the lamp, when in place, is put in electrical connection with the conductors $a a^2$, one of which latter, a , is in direct electrical connection with the 5 spring H , being fastened or otherwise electrically connected with the end thereof, as shown, while the other is fastened to the end of spring E , and is connected with H^2 , when the cam D is in the position shown, through E 10 $G g G^2 E^2$.

As will be observed, the circuit from H^2 to a^2 passes through switch-contacts $G G^2$ in series, and the effect of operating the switch is to break the circuit in two places. This is a 15 feature of some importance, as it is largely instrumental in reducing the spark at rupture of the circuit over what would result if but one break were made in the circuit, as is ordinarily the case. This principle might obviously 20 be extended and the break of circuit made to take place at three, four, or more points in series, by increasing the number of switch-contacts and springs electrically connected in series and operated simultaneously by any suitable means.

The block B and its attached parts form a separable part of the structure, and may be 25 separately constructed from the other parts and then put in place in the structure by simply attaching the block B to the base-plate A . When the connections of the conductors $a a^2$ are to be made with the switch, the case or cylinder is removed, and ready access to the parts is thus secured.

30 An incandescent lamp of any usual construction is indicated at I , and its neck is supported in a spring-clip (indicated at K) that rises from or forms a part of a metallic cylinder or envelope, L , secured to a block, M , of insulating material. The latter forms the lamp base or support proper, and carries the terminals or devices by which contact is made with the springs $H H^2$, as well as clips or connection by which immediate connection is 35 made with the lamp-conductors passing from the lamp itself. The latter devices consist of two spring-clamps, $i i^2$, into which the exterior ends of the entering conductors pass, and in which they are secured by the clamp-screws indicated. The lamp-base M carries also the 40 fastening devices by which the lamp is secured to the holder or socket formed by the upper end of cylinder C , so as by means of springs $H H^2$ to be in connection with the conductors $a a^2$. The latter device consists, simply, of 45 two pins or lugs, $n n$, on block or base M , that are adapted, after the lamp is inserted properly and turned in its socket, to be brought into place beneath the projections $p p$ at the 50 upper and inner side of cylinder C , as indicated in Fig. 7, so as to hold the lamp in place on C , after the manner of a bayonet-joint. The lamp is held from turning back to a position where it may be removed by means of the 55 incline formed by the turned-down ends of the springs $H H^2$, upon which the ends of the pins $m m^2$ in base M rest, in the positions indicated

in Figs. 2 and 3, when the lamp is turned in its socket so as to be locked by the bayonet-joint attachment described.

The pins $m m^2$ are electrically connected with the clips $i i^2$, and therefore with the entering-conductors of the lamp, as follows: Pin m is a screw, by which the clamp i is fastened to the base M . Pin or stud m^2 is connected with i^2 through a piece of lead wire or other suitable fusible material, r , forming a safety plug or wire that is of suitable resistance and fusibility to melt upon a rise in the strength of the current that would endanger the incandescent-strip in the lamp. The fusible plug r lies in a slot or recess in the side of base M , and at one end is clamped between the end of a screw, r^2 , that fastens clamp i^2 to the base M , and the end of a screw-pin, r^3 , passing upward from the bottom of the base-block into the slot in which the wire r lies. The other end of the wire is clamped between the end of the screw pin or stud m^2 and the end of a screw, t , passing downward from the top of the block.

In Fig. 3 the lamp-base M is shown reversed in position from the position shown in Fig. 2, and the connecting-pins are thrown out of line in order to better exhibit the mechanical and 95 electrical relation of the parts. When the base M is in position, as shown in Fig. 3, the circuit is from the one connecting-spring H , through contact stud or pin m^2 , fusible wire r , clamp i^2 , the wires and filament of the lamp, (when the latter is attached to its base-block,) 100 clamp i , conducting-pin m , and to spring H^2 at the top of the switch-block B .

In case of destruction of a fusible plug, r , the lamp and its base are simply removed 105 from the socket or support formed by the upper end of cylinder C , and the plug may then be readily removed without disturbing the lamp socket or support or the parts forming or containing the switch. The block B keeps the 110 parts well insulated, and the case C forms ample protection. The operating parts of the switch are out of contact with the inner side of said cylinder C , which, being of metal, should be of sufficient size to leave ample space between its interior surface and the surfaces of the block and switch contacts and springs.

The switch mechanism is capable of being turned in either direction, and no damage can therefore result, as in some other switches, from 115 an attempt to turn it in a reverse direction from that designed by the constructor.

If no switch be employed, the construction indicated in Figs. 8 and 9 is adopted. The block B simply differs slightly in form from 125 that shown in the other figures, and the conductors $a a^2$ are clamped beneath the springs $H H^2$, or otherwise connected to them, the latter being in this case fastened to the top of the block B . In other respects the construction is the same as already described.

Modifications in the form, mounting, or disposition of the fusible plug may be readily made without departing from the invention,

the feature of novelty on which I lay particular stress being the mounting of the fusible plug in the lamp-base proper, so that on detaching the lamp from its socket or support 5 the fusible plug will at the same time be removed.

The block B, as mounted and protected, might be readily employed for the supporting of switches of other forms or constructions.

10 The device of turning down the ends of the connecting-springs H H² is obviously adapted for use with any means of holding together the parts against tendency to vertical displacement.

15 What I claim as my invention is—

1. A base-plate or support for an incandescent lamp adapted for attachment to a bracket or other suitable support, and having an opening for the conducting-wires, in combination 20 with an insulated block carried by said plate, and an electric switch and binding-screws for the conductors attached to the exterior of said block, said block and switch being independent of, but placed within the usual casing or 25 block for the various parts, whereby, on detaching said casing, all parts of the switch and connecting devices are exposed upon the block for ready manipulation.

2. In a switch and lamp-support for incandescent electric lamps, a block, B, of insulating material, having a support for the switch mechanism, and cut away at its bottom to allow a passage for the conductors a a², said block being independent of the metal casing 35 within which it is supported.

3. In an incandescent-lamp switch, the combination, with the vertically-arranged switch-spring mounted on a vertically-slotted insulating-block, of the cam-piece rotating in the 40 slot between the springs, and a transverse spindle extending through the metal casing and carrying at one end the cam, and at its outer end an operating thumb-piece, as and for the purpose described.

45 4. The combination, in an electric switch, of the two contact-springs fixed at one end and free at the other, contact blocks or anvils arranged opposite the free ends and outside of the same, a metal connection from one anvil 50 or block to the other, and an operating cam-piece mounted on a spindle passing transversely between the springs, whereby on rotating the spindle the springs may be thrown simultaneously into or out of contact with the 55 anvils, and the circuit may be thus broken at two points.

5. The combination, with the vertically-slotted non-conducting block, of the two vertical springs, the electrically-united stops projecting over the slot into the path of the springs, and the cam of insulating material adapted to be turned in the slot and between the springs. 60

6. The block B, of insulating material, carrying the vertically-arranged switch-springs, 65 and the horizontal contact-springs arranged on top of the block for the purpose of forming connection with the lamp-terminals.

7. In an incandescent-electric-lamp switch and support, an insulating block or support carrying the switch mechanism and detachably secured to the base-plate, and a separable metallic or other casing supported on said base independently of the block.. 70

8. In an incandescent-electric-lamp switch and support, the combination, with the perforated base-plate A, adapted for attachment to a bracket or other support, of an attached supporting-block, B, carrying the switch mechanism, and a separable metallic casing, C, as and for the purpose described. 75

9. The combination, with the removable incandescent lamp, of contact springs having turned-down ends, contact studs adapted to bear on said springs, and a bayonet-joint catch, as and for the purpose described. 80

10. The combination, with a detachable lamp and its socket or support, of electric connecting devices consisting of one or more contact-studs secured to the one of the parts, and one or more contact-springs secured to the other part and having bent-down ends, said studs being adapted to make rubbing contacts with the springs and to rest upon the turned-down ends when the lamp is turned in its socket or support to proper position, as 90 and for the purpose described. 95

11. The combination, with the lamp-base proper for an incandescent electric lamp, of means for securing a fusible plug in the base, whereby the plug may be replaced on removal of the lamp from its support without disturbing the connections in said support or 100 socket.

12. The combination, with the lamp-base proper, of a slot or groove in the side of said base, and means for holding a fusible plug in place in said groove, as and for the purpose described. 105

13. The combination, with the incandescent lamp, of the base M, of insulating material, removable with the lamp from the socket or support for the latter, and a fusible plug or wire, and means for clamping said plug or wire in the base, as and for the purpose described. 110

14. The combination, with an incandescent 115 electric lamp, of a base, M, of insulating material, removable with the lamp from the socket or support for the latter, a fusible plug or wire lying in a slot or groove in the side of the base, and clamp-screws for clamping the plug in 120 contact with conducting pins or blocks, whereby it may be made to form a portion of the circuit in which the lamp is placed.

15. The combination, with the lamp-base proper for an incandescent lamp, of means for holding a fusible plug or wire in circuit with the filament, whereby when the lamp is removed from its socket the parts securing the plug or wire will also be removed and a new plug or wire may be readily inserted. 125

16. The combination, with an incandescent electric lamp, of a socket or holder for supporting the same, contact springs or surfaces carried by the lamp and its socket or holder, 130

respectively, whereby electrical connection between the lamp and the outside conductors will be made when the lamp is placed in its socket, and a fusible plug between the lamp-
5 filament and the contact-surfaces carried by said lamp, as and for the purpose described.

17. The combination, with the metal case or tube mounted in base-plate A, of the sleeve L, carrying the insulating-base M for the lamp, a
10 block of insulating material rising within the case from the plate A and carrying the lamp-

switch mechanism, contact - surfaces in the block and base M, respectively, and means for connecting the sleeve to the metal case or tube, as and for the purpose described.

15 Signed at New York, in the county of New York and State of New York, this 12th day of March, A. D. 1884.

WILLIAM HOCHHAUSEN.
